UNITED STATES PATENT OFFICE

JOHN ROBERT CAMPBELL, OF BURNABY, ONTARIO, CANADA

COMBINED FLOOR WAXER AND POLISHER

Application filed December 29, 1928. Serial No. 329,141.

My invention relates to improvements in combined floor waxes and polishers of the type disclosed in my United States Patent #1,572,987, dated February 16th, 1926, and in my Canadian Patent #227,687, dated January 9th, 1923, and the object of the present invention is to devise a device of this type in which the waxing and polishing elements may be readily converted with maximum ease for performing either the waxing or polishing operation as desired, in which the wax may be easily, quickly and evenly applied to the element, in which the throwing of wax from the element by centrifugal action onto other parts of the machine is prevented, in which locking means is provided for detachably securing the element in the machine and which at the same time holds the element from end play, and in which the waxing and polishing device is so constructed as to wax and polish right up to the lower bead of the wainscot, and it consists essentially of the arrangement and construction of parts as hereinafter more particularly explained.

Fig. 1 is a general perspective view of my waxing and polishing machine.

Fig. 2 is a sectional plan view showing the means for permitting of the easy insertion and removal of the waxing element.

Fig. 3 is a plan detail view of the waxing element removed from the machine showing the felt pad and wrapper in section.

Fig. 4 is a vertical sectional view through Fig. 3, taken on line 4-4.

Fig. 5 is a transverse sectional view on line 5-5 Fig. 4.

Fig. 6 is a transverse sectional view on line 6-6 Fig. 4.

Fig. 7 is a perspective detail of the locking device for securing the waxing or polishing element in the machine.

Fig. 8 is a perspective detail of the end stud of a waxing or polishing element with which the locking device coacts.

Fig. 9 is a sectional view through the various parts forming the snap connection between the wrapper 26 and the core 13, such parts being spaced apart.

In the drawings like characters of refer-

ence indicate corresponding parts in each figure.

1 indicates the main casing or housing of my waxing and polishing device. The side wall 1^x of the housing is flared outward at 1°, the flared out portions being provided with a cut away recess 2 extending from the point at which the flare commences to the forward extremity of the machine. By this means an opening is formed which will permit the casing passing over the base bead of a skirt board so that the waxing or polishing element of the machine may operate close up to the bead as will hereinafter appear.

The side wall 1^x of the housing is provided in its front edge with an open ended slot 3. The opposite wall 2^x is provided with a stationary stud 4 secured to the wall by screws 4^x and on which is mounted an inner race 5 of a ball bearing.

6 is the outer race of the bearing and 7 the balls. The outer race 6 is secured within a recess 8 formed in the driving pulley 9. By this means the driving pulley 9 is rotatably mounted on the stud 4. 10 is the operating motor of the machine and 11 the driving pulley secured to the motor shaft. 12 is a driving belt extending around the driving pulley 11 at one end and around the pulley 9 at its opposite end. The inner face of the pulley 9 is convexed as indicated at 9^x and the convexed face is provided with a central rectangular opening 9°. The edges of the orifice 9° may be chamfered off for a purpose which will hereinafter appear.

13 is the centre cylindrical core of a waxing element provided at one end with a stationary stud 13^x, the edges of which are also chamfered off to permit of the easy insertion of the stud into the orifice 9°. The opposite end of the cylindrical core 13 is provided with a cylindrical stud 14 provided with a rectangular projection 14^x extending outward therefrom and adapted to fit into the open ended slot 3 of the casing.

The inner portion of the stud 14 is reduced as indicated at 14°, such reduced portion being driven into the inner race 15 of a ball bearing, the outer race 16 of the bearing be-

ing secured in the end of the cylindrical core 13.

17 are the balls of the bearing.

By this means the cylindrical core 13 is 5 revolvably mounted within the casing and driven from the motor through pulleys 11 and 9 and belt 12.

In order to detachably lock the core in 10 the machine I provide the following device.

18 is a slot formed in the side wall 1^x of 15 the machine provided at its forward end with a downwardly extending portion 18^x.

19 is a locking member provided adjacent 20 its lower end with a right angular arm 19^x 25 which is pivoted at 20 to the wall 1^x of the machine. The slot 18 is concentric with the pin 20. The upper end of the locking member 19 is provided with a longitudinal slot 19°.

21 is a button which bears against the 20 outer face of the wall 1^x and is provided with a central stud 22 which extends through the slots 18 and 19°, the inner end of the stud being suitably enlarged to prevent its outward withdrawal.

28 The stud 14 is cut away around the rectangular projection 14^x so as to form a recess 23 which extends to the front and top faces of the projection 14^x as clearly indicated in Fig. 8. The edge of the stud extending between 30 the recess is bevelled or rounded off as indicated at 24.

The button 21 is forced forward through the slot 18 opposite to the inclined extension thereof. When in this position the inner edge of the locking member 18 below the arm 19^x fits into the recess 23 against the forward face of the stud 14^x, the lower edge of the arm 19^x fitting in the recess against the upper face of the stud.

40 After the locking member has been so operated the stud 21 is forced longitudinally of the locking member 18 so as to carry the stem 22 of such stud longitudinally of the slot 19° into the slot extension 18^x, thereby 45 preventing the inadvertant return movement of the locking member.

By this means it wil be seen that the stud 14^x is securely locked within the slot 3 from outward movement.

50 25 is a cover formed of felt. The cover 25 is cylindrical and fits over the core 13. 26 is wrapper which is detachably secured at its ends to the core 13 in an overlapping position.

55 When the element is used as a waxing element the wrapper 26 is made of comparatively coarse fabric through which the wax may penetrate. When the wrapper is used 60 as a polishing means it is made of felt or other suitable material through which the wax will not percolate and which is soft so as to have a polishing effect.

I will now describe the means by which 65 the wrapper when either made of the coarse

fabric or of the felt may be detachably secured to the core.

27 is a groove extending longitudinally of

the core 13 from end to end. 28 is a plate which is arched transversely to correspond 70 with the periphery of the core 13 and is countersunk in the surface of the core so as

to extend over the groove 27. 28^x are ori- 75 fices formed in the plate 28 at suitably spaced apart positions.

29 are cylindrical socket members extending outward around the orifices 28^x and provided with spring 80 snap ends 29^x.

30 are cylindrical extensions to the socket members extending inwardly 85 of the plate 28 and are provided at one side with vertically slotted openings 30^x from

which extend guide walls 31 and 32. 33 and 34 are plates forming the ends of the 90 groove 27.

35 and 36 are bearing blocks secured transversely within the groove 27 by screws 35^x and 36^x.

37 is a rod which is secured in the bearing blocks 35 and 36 by securing pins 37^x.

38 is a rod which is slidably held within the bearing blocks 35 and 36 so as to move 95 longitudinally.

39 are finger pieces which are pinned or otherwise suitably secured as indicated at 40 to the rod 38.

41 are hooked catches provided with inclined upper ends 41^x.

The hooked catches 41 are provided with sleeves 41° which are slidably held upon the rod 37 and are spring pressed against 100 the finger pieces 39 by compression springs 42 bearing at their outer ends against pro- 105 jections 43.

The rod 38 extends at one end through an orifice 33^x in the plate 33 and is provided at its outer end with a thumb 110 button 44 by which the rod 38 may be moved

by the pressure of the thumb of the operator upon the thumb button, thereby moving the 115 finger pieces 39 forward to engage the catches 41 to simultaneously carry them in and out of their engaging position.

The wrapper 26 is provided along one 120 end edge with a series of eyelets 45 which

are adapted to be snapped into engagement with the spring ends 29^x of the cylindrical 125 socket members 29.

The wrapper 26 is then passed around the felt covering 25 in the direction of arrow, see Fig. 5.

The opposite end of the cover 25 is provided with a series of pin projections 46 adapted to fit 130 the socket projections 29 so as to extend therethrough into the extension 30.

Each pin 46 is provided with a longitudinal 135 slot 47 which when the pin is inserted is

opposite the interspace between the walls 31 and 32.

The inner end of the pin 46 is prefer- 140 ably rounded off and the slot 47 tapered for a purpose which will hereinafter appear.

The felt cover 25 is provided with ori- 145 fices 25^x through which the socket members 29 extend.

The wrapper 26 particularly when used for waxing is preferably applied to the element by first snapping the eyelets

into engagement then laying the wrapper on the floor in front of the element, then spreading the wax on the upper face of the wrapper and then operating the machine 5 forward so as to rotate the element and wind the wrapper thereon, the pins 46 then being inserted into the sockets for engagement.

The wrapper when passed around the 10 waxing element retains the wax between the wrapper and the felt covering 25, the opposite end of the wrapper being then secured by individually passing each of the pins 46 into their respective sockets 29. As 15 each pin 46 is inserted it engages the inclined upper end 41^x of the corresponding catch 41, thereby forcing such catch longitudinally on the rod 37 against the pressure of the spring 42, the pin 46 then passing 20 downward so that the hook end of the catch springs into engagement with the slot 47.

It will thus be seen that each pin 46 is individually engaged so that the free end of the wrapper may be readily buttoned into 25 position.

The upper end of the catches 41 are also tapered laterally and the slots 47 as before stated are correspondingly tapered so as to permit of the ready entrance and centering of the hook end of the catch.

In order to limit the return movement of the rod 38 I provided a pin projection 45^x extending therefrom to engage the bearing 35.

From what has been before set forth it will be readily understood that the hook catches 41 may be simultaneously released by pressing upon the thumb button 44 so as to operate the rod 38 longitudinally and the 40 catches as has been before set forth.

When it is desired to remove the coarse fabric wrapper so as to attach the polishing wrapper all it is necessary to do is to press upon the thumb piece 43, thereby relieving 45 one end of the attached wrapper, unwrapping such wrapper and pulling the eyelets 45 out of engagement with the spring ends 29^x of the sockets 29 and then applying the felt wrapper which is simultaneously engaged in 50 the spring sockets 29^x, wrapped around the cylindrical felt wrapper and engaged by the buttoning action hereinbefore described in relation to the coarse fabric wrapper.

When the felt wrapper is used the eyelets 55 instead of being directly attached to the felt are preferably attached to a strip of fabric secured to the end edge of the felt and the corresponding pins 46 to a similar strip of fabric secured to the opposite end edge of the felt. 60 By this means the increased thickness of material is compensated for at the overlapping ends of the wrapper.

If desired instead of using the polishing wrapper as above described a separate element 35 may be employed consisting of a cylin-

drical brush provided with end projections corresponding to those employed in connection with the waxing and polishing element above described.

The waxing and polishing element may be 50 easily removed by operating the thumb button 21 so as to remove the locking arm 19 out of engagement with the stud 14^x. The corresponding end of the element is then swung 55 outward so as to carry the stud 14^x through the open end of the slot 3, the rounded edge 24 permitting of the stud passing freely in this direction.

As this movement takes place the element is carried from the full line position to the 60 dotted line position indicated in Fig. 2, the opposite end of the element having a rolling action against the convexed face of the pulley 9 so that the outwardly swung end of the element will be carried clear of the wall 1^x so that it can then be moved longitudinally to carry the projection out of the orifice 9^x. The brush may then be inserted by a reverse operation, that is, placing the brush in the dotted line position shown in Figure 2 with one end 65 in contact with the convexed face of the pulley 9, then swinging the brush inward so as to carry the projection into the orifice 9^x and permitting the opposite end of the brush to enter within the wall 1^x of the casing and the 70 stud 14^x into engagement with the slot 3.

It might be pointed out that the cover 10 is suitably insulated from the casing 1 and a fibre or other insulating material may be 75 inserted between the stud 4 and the pulley 9 as indicated at X and the stud 14^x may be 80 also made of fibre or other suitable insulating material. It will thus be seen that the 85 whole machine is thoroughly insulated and is as noiseless as it is possible to make a machine of this type.

What I claim as my invention is:

1. In a combined floor waxer and polisher, a waxing or polishing element comprising a centre cylindrical core, a cushioning member covering the peripheral surface of the core, a fabric wrapper extending around the cushioning member and attached along its free opposing edges to the core, such attaching means comprising eyelets secured to the wrapper adjacent one transverse edge thereof, spring members carried by the core and extending through the cushioning member and adapted to snap into the open centres of the eyelets, and means for detachably securing the opposite edge of the wrapper to the core in a position overlapping the aforesaid wrapper edge.

2. In a combined floor waxer and polisher, a waxing or polishing element comprising a centre cylindrical core, a cushioning member covering the peripheral surface of the core, a fabric wrapper extending around the cushioning member and attached along its free opposing edges to the core, such attaching 120 means comprising eyelets secured to the wrapper adjacent one transverse edge thereof, spring members carried by the core and extending through the cushioning member and adapted to snap into the open centres of the eyelets, and means for detachably securing the opposite edge of the wrapper to the core in a position overlapping the aforesaid wrapper edge.

means comprising eyelets secured to the wrapper adjacent one transverse edge of the wrapper, cylindrical socket members having spring outer edges carried by and projecting from the core and through the cushioning member and with which the eyelets are snapped into engagement, pins secured to the opposing overlapping edge of the wrapper and adapted to fit and pass through the socket members, and spring snaps carried by the core and having locking engagement with the inwardly projecting ends of the pins.

3. In a combined floor waxer and polisher, a waxing or polishing element comprising a centre cylindrical core, a cushioning member covering the peripheral surface of the core, a fabric wrapper extending around the cushioning member and attached along its free opposing edges to the core, such attaching means comprising eyelets secured to the wrapper adjacent one transverse edge of the wrapper, cylindrical socket members having spring outer edges carried by and projecting from the core and through the cushioning member and with which the eyelets are snapped into engagement, pins secured to the opposing overlapping edge of the wrapper and adapted to fit and pass through the socket members, a plurality of securing means carried by the core and adapted to individually engage the pins when forced into the socket members, and means for simultaneously releasing the pins from such securing means.

35. 4. In a combined floor waxer and polisher, a waxing or polishing element comprising a centre cylindrical core having a chamber extending longitudinally of the core, a cushioning member covering the peripheral surface of the core, cylindrical socket members having spring edges projecting outward from the core through the cushioning member and inward into the aforesaid chamber, a fabric wrapper passing around the cushioning member, eyelets adjacent one transverse edge of the wrapper adapted to snap into engagement with the socket members, pins having orifices adjacent their extremities secured to the wrapper along its other transverse edge adapted to fit or pass through the socket members, a stationary rod mounted in the chamber, spring pressed catch members movably mounted upon the rod having downwardly inclined upper ends with which the pins engage as they are inserted to move the members upon the rod against the aforesaid spring pressure, laterally projecting portions at the upper ends of such members adapted to enter the orifices of the pins when such orifices are brought into alignment therewith, a longitudinally movable rod also mounted in the chamber and projecting through one end thereof, finger pieces secured to the movable rod and projecting laterally therefrom to engage the opposite end of the catch members.

65. 5. In a combined floor waxer and polisher,

a waxing or polishing element comprising a central cylindrical core having a chamber extending longitudinally of the core, a cushioning member covering the peripheral surface of the core, cylindrical socket members having spring edges projecting outward from the core through the cushioning member and inward into the aforesaid chamber, a fabric wrapper passing around the cushioning member, eyelets adjacent one transverse edge of the wrapper adapted to snap into engagement with the socket members, pins having orifices adjacent their extremities secured to the wrapper along its other transverse edge adapted to fit or pass through the socket members, a stationary rod mounted in the chamber, catch members spring pressed at one end and movably mounted upon the rod having downwardly inclined upper ends with which the pins engage as they are inserted to move the members upon the rod against the aforesaid spring pressure, laterally projecting portions at the upper ends of such members adapted to enter the orifices of the pins when such orifices are brought into alignment therewith, a longitudinally movable rod also mounted in the chamber and projecting through one end thereof, finger pieces secured to the movable rod and projecting laterally therefrom to engage the opposite end of the catch members.
